(57) **CLAIM**

The ornamental design for a T.V. turntable, as shown and described.

DESCRIPTION

FIG. 1 is a top perspective view of the T.V. turntable;

FIG. 2 is a top plan view thereof;

FIG. 3 is a bottom plan view thereof;

FIG. 4 is a front view thereof;

FIG. 5 is a rear view thereof; and,

FIG. 6 is a right side view thereof.

The broken line showing of a plug is for illustrative purposes only and forms no part of the claimed design.
